US00D941309S

(12) **United States Design Patent** (10) **Patent No.:** **US D941,309 S**
(45) **Date of Patent:** **** Jan. 18, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Patrick Lee Coffman**, San Francisco, CA (US); **Raymond Sepulveda**, San Jose, CA (US); **Chun Kin Minor Wong**, Cupertino, CA (US)

(73) Assignee: **Apple Inc.**, Cupertino, CA (US)

(**) Term: **15 Years**

(21) Appl. No.: **29/733,283**

(22) Filed: **Apr. 30, 2020**

Related U.S. Application Data

(63) Continuation of application No. 29/642,271, filed on Mar. 28, 2018, now Pat. No. Des. 884,715, which is a continuation of application No. 29/582,324, filed on Oct. 27, 2016, now Pat. No. Des. 815,139.

CLAIM

The ornamental design for a display screen or portion thereof with graphical user interface, as shown and described.

DESCRIPTION

The sole FIGURE is a display screen or portion thereof with graphical user interface showing our new design.

The peripheral dashed broken lines represent a display screen or portion thereof, and form no part of the claimed design. The dotted broken lines represent boundaries which form no part of the claimed design and the faded portions within the dotted broken lines form no part of the claimed design.
